UNITED STATES PATENT OFFICE.

FLEMING CLAY RAWLEY, OF DUBLIN, KENTUCKY.

DESIGN FOR A MEAT-HOOK.

SPECIFICATION forming part of Design No. 31,631, dated October 10, 1899.

Application filed September 15, 1899. Serial No. 730,638. Term of patent 7 years.

To all whom it may concern:

Be it known that I, FLEMING CLAY RAWLEY, a citizen of the United States, residing at Dublin, in the county of Graves and State 5 of Kentucky, have invented and produced a new and original Design for a Meat-Hook, of which the following is a specification.

In the accompanying drawings, forming a part of this specification, Figure 1 is a view 10 in elevation of a meat-hook, illustrating my new design. Fig. 2 is a sectional view taken on the line $x-x$ of Fig. 1, looking in the direction of the arrow.

As shown in the drawings, the leading or 15 material feature of my design consists of a ring or coil 1, the terminal portions 2 of which are extended in substantially parallel relation to each other and tangentially to the ring or coil, and the end portions or extremities are 20 extended outwardly and divergently in the form of oppositely-located hooks 3, as clearly shown in Fig. 1. The terminal portions 2 are joined by a connecting-stay 4, which bears an approximately tangential relation to the lower 25 portion of the coil or ring 1. The terminal portions 2 extend below or beyond the connecting-stay 4, and their recurved extremities are extended obliquely outward, terminating approximately in a line with the stay 4. The

stay, as shown, is passed through the lower 30 portion of the coil or ring with its extremities recurved or bent back upon the terminals 2.

The design as a whole resembles the capital letter **W**, being distinguished therefrom by the formation of the coil or ring at the central upper portion and the cross-piece or stay, which bears a tangential relation to said ring or coil and reaches to the terminal portions before the latter are extended upward to form the hooks 3. It also differs therefrom in that 35 the extremities are terminated in line with the stay 4 and are not extended to the plane of the extreme upper portion of the article.

While the design is described as particularly applicable to meat-hooks, it is also applicable to similar or analogous articles. 40

Having described my invention, what I claim as new, and desire to secure by Letters Patent, is—

The design for a meat-hook, as herein shown 45 and described.

In testimony that I claim the foregoing as my own I have hereto affixed my signature in the presence of two witnesses.

FLEMING CLAY RAWLEY.
